UNITED STATES PATENT OFFICE.

HARLEY D. APPS AND LEWIS S. LOW, OF DOLPH, MICHIGAN.

FIREARM.

Specification of Letters Patent.

Patented Feb. 6, 1917.

1,314,934.

Application filed April 11, 1916, Serial No. 90,499. Renewed December 1, 1916. Serial No. 134,561.

To all whom it may concern:

Be it known that we, HARLEY D. APPS and LEWIS S. LOW, citizens of the United States, residing at Dolph, in the county of Missaukee and State of Michigan, have invented certain new and useful Improvements in Firearms; and we do hereby declare the following to be a full, clear, and exact description of the invention, such as will enable others skilled in the art to which it appertains to make and use the same.

Our invention relates to new and useful improvements in firearms and our object is to provide a device of this class wherein the projectile is propelled from the barrel of the firearm by the explosion of commingled air and liquid explosive material.

A further object is to provide means for successively feeding a projectile into the barrel of the firearm.

A further object is to provide a compression chamber and a controlling valve therefor.

And a further object is to provide a water jacket around the barrel and compression chamber for cooling purposes.

Other objects and advantages will be hereinafter set forth and more particularly pointed out in the accompanying specification.

In the accompanying drawings which are made a part of this application,

Figure 1 is a central longitudinal sectional view through the firearm, and

Fig. 2 is an enlarged transverse sectional view as seen on line 2-2 of Fig. 1.

Referring to the drawings in which similar reference numerals designate corresponding parts throughout the several views, 1 indicates the barrel of the firearm which may be constructed in the usual or any preferred manner, said barrel terminating at one end in a compression chamber 2, said barrel being separated from the compression chamber by means of a rotating valve 3, said valve having a channel 4 through which the explosive substance is discharged into the barrel when turned in one direction and a solid portion 5 which closes communication between the barrel and compression chamber when the valve is turned in a certain position, said valve being manually or automatically rotated in any suitable manner.

Surrounding the barrel and compression chamber is a casing 6 which forms a water

jacket 7 the full length of the barrel and around the compression chamber, thereby keeping the barrel and compression chamber in a cool state when in use.

The projectiles 8 are deposited in a hopper 9 and may be either round or oblong as desired, said hopper being preferably mounted upon a projection 10 extending laterally from the barrel 1, said projection having a slot 11 therethrough in which is mounted a slide block 12, said slide block having a vertical bore 13 into which the projectiles descend from the hopper 9. The length of the slide block is such that one end thereof projects a distance beyond the end of the slot 11 whereby pressure may be applied thereagainst for moving the block lengthwise, and when the block is moved its full distance in one direction the bore 13 will register with the opening in the lower end of the hopper and with the opening of the barrel 1 when moved its full distance in the opposite direction and when in the latter position the projectile will descend into the barrel immediately forwardly of the valve 3.

The propelling force for the projectile preferably consists of properly commingled air and gasoline although any other similar explosive substance may be used, said air and explosive substance being conveyed into the compression chamber 2 through a pipe 14. After a proper amount of the explosive substance has been discharged into the compression chamber it is exploded by forming an electric spark through a spark plug 15, or in any other manner, and coincident with the explosion of the gases within the compression chamber the valve 3 is turned until the channel 4 registers with the opening of the barrel and compression chamber, thereby delivering the force of the explosion directly against the projectile and discharging the same from the end of the barrel with great force.

The interior of the compression chamber is drained through a drain pipe 16, while the water jacket is drained through a bib cock 17.

This form of firearm can be very rapidly fired and by providing the water jacket the parts of the firearm will be kept in a cool state so that the explosion of the gases therein will not affect the parts of the barrel or compression chamber.

It will further be seen that by the em-

ployment of gases for discharging the projectile a greater number of shots may be fired at a much less expense than when powder is used and that the handling of the firearm will be greatly simplified and much more convenient.

It will likewise be seen that this device can be very cheaply constructed and is practically indestructible from use.

10 Having thus fully described our invention what we claim as new and desire to secure by Letters Patent of the United States, is:—

1. In a firearm, the combination with a barrel, of a projection extending laterally from the barrel, said projection having a longitudinally extending slot therethrough, a slide block mounted in said slot, said slide block having a vertical bore, and a projectile containing hopper positioned on said extension and at one side of the barrel, said hopper having an opening communicating with the bore in the slide block, whereby when the slide block is moved out-
- 15
- 20

wardly a projectile will descend in said bore 25 and be deposited in said barrel when the slide block is moved inwardly.

2. In a firearm, the combination with a barrel, of a projection extending laterally from the barrel, said projection having a 30 longitudinally extending slot therethrough intersecting the bore of the barrel, a frusto conical hopper carried by that portion of the projection beyond the barrel, said hopper being adapted to contain projectiles, a 35 slide block having a vertical bore therein adapted to receive a projectile from the hopper, and convey the same into the said barrel when the slide block is moved inwardly.

In testimony whereof we have signed our 40 names to this specification in the presence of two subscribing witnesses.

HARLEY D. APPS.
LEWIS S. LOW.
